Application January 9, 1942, Serial No. 426,156

3 Claims. (Cl. 38—15)

1

This invention relates to machines for pressing garments and the like and has for its general objects to improve the pressing performance of, or quality of the work performed by such machines and increase the ease, facility, convenience and speed of their operation. The present application is a continuation in part, and with respect to certain common subject matter, of a prior application filed December 10, 1940, Serial No. 369,448, now Patent No. 2,348,264, granted May 9, 1940, but shows and describes the invention in an improved and further developed form. The claims hereunto appended cover the aforesaid common subject matter generically as well as, more specifically, the further developments and improvements referred to.

A pressing machine of the type to which the present invention relates comprises a pair of co-operating press elements or presser members which are relatively movable toward and from one another to cause them to close upon and exert and (for a suitable time) maintain pressure upon work interposed between them and thereafter open to release the pressure and work. Usually there is provided a lower stationary member, or so-called buck, and an upper member, or so-called head, movable toward the buck to exert pressure upon work disposed on the latter and away from the buck to release the pressure and permit the removal and insertion of the work. Means are sometimes provided for applying a moistening medium (usually spray steam) and a drying medium (usually heated air) to the work before, during, or after the pressing operation, but such means have usually been manually controlled, so that the time and duration of the application of the respective media, with respect to the pressing operation, have depended upon the skill and judgment of the operator and, even in the hands of the most experienced operators, have not been such as to produce the most satisfactory results. In some cases it has been proposed to correlate the admission of the respective media with the closing and opening movements of the press elements, but in none of these, so far as we are aware, has the relative timing been such as to accomplish the desired end. This has been due to the failure of the inventors of such machines to appreciate the factors of the problem. Attempts have been made to improve the pressing performance by increasing the pressure upon the work, but this leads to undesirable consequences, such, for example, as the formation of conspicuous seam fold markings upon the work. We have discovered that great pressure is not

2

necessary to the highest quality pressing, but that the determining factor is the proper and accurate timing of the application of moisture and the drying out process with respect to each other and the exertion of pressure. More particularly, we have found that the best results are obtained by admitting steam to the work when the press elements are closed, and by cutting off the steam and applying the drying medium to the work both while the latter is held under the substantially constant maximum (but not excessively heavy) pressure for which the machine is designed or adjusted. The present invention has for its primary object the provision of mechanism for performing these operations automatically, reliably, accurately, and without attention on the part of the operator, whereby work of uniformly high quality may be turned out by relatively unskilled and inexperienced operators.

10 The invention also has for an object to provide improved means for applying the drying medium (or heated air) to the work, and carrying away the moisture from the latter, in accordance with which said medium is most effectively and evenly applied, whereby the work under pressure is evenly and quickly dried.

20 Another object of the invention is to provide improved means for controlling and limiting the pressure exerted upon the work by the press elements.

30

The invention will best be understood from the following description of an illustrative embodiment thereof shown in the accompanying drawings, although it will be apparent to those skilled in the art that said invention, as defined by the claims hereunto appended, may be otherwise embodied without departure from its spirit and scope.

35 In said drawings:

40 Fig. 1 is a side elevational view, partly in section, of a machine embodying the invention;

45 Fig. 2 is a front elevational view of the same, partly in section;

50 Fig. 3 is a plan view of the same;

55 Fig. 4 is a fragmentary view similar to Fig. 1 showing the parts in different positions;

Fig. 5 is a detail fragmentary sectional view similar to Fig. 1;

Fig. 6 is a sectional view taken substantially on the line 6—6 of Fig. 2;

Fig. 7 is a sectional view taken substantially on the line 7—7 of Fig. 6;

Fig. 8 is an enlarged detail front sectional elevational view of a portion of a machine;

Fig. 9 is an enlarged detail view of a portion of a machine as viewed in Fig. 7;

Fig. 10 is a sectional view taken substantially on the line 10—10 of Fig. 9; and

Fig. 11 is a diagrammatic view illustrating the timed relation in the operation of certain parts of the machine.

The machine illustrated comprises a main frame 10 of box-like form having upper front and rear frame members 11 and 12, respectively, supported thereon (Figs. 1, 2, 3 and 4). A buck 15 is secured upon the front frame member 11 by bolts 16. The rear frame member 12 is provided with means for supporting and guiding a movable presser member or head 14 for movement toward and away from the buck 15. For this purpose a shaft 17 (Figs. 1, 3 and 4) is slidably mounted in vertically spaced bearings 18 and 19 formed in the frame member 12. A ring 20 is secured to the shaft 17 between the bearings 18 and 19 by a set screw 21. The ring 20 is provided with a forwardly extending key 22 adapted to engage a vertical groove 23 in the frame member 12. A pair of spaced parallel L-shaped arms 25 are pivotally mounted intermediate their ends upon aligned trunnions 24 integral with the ring 20. The head 14 is secured to the forward ends of the arms 25. Rollers 30 (Figs. 1 and 4) are mounted upon depending portions of the arms 25 near their lower ends and each roller is adapted to engage a cam groove 31 formed in a plate 32 secured to the frame member 12. Each groove 31 has a vertical portion 33 which allows the head 14 to rise or fall vertically before entering or after leaving the arcuate portion 34 having a radius of curvature such as to permit the arms 25 to swing about the axis of the trunnions 24.

Spaced supports 35 (Figs. 1, 2 and 4) of inverted U-shape are carried by spaced rods 36 extending between the side walls of the frame 10. A main drive shaft 38 is mounted for rotation in bearings in the side walls of the frame 10 and in each of the supports 35. A worm wheel 39 fixed upon the shaft 38 engages a worm 40 fixed upon a counter shaft 41 which is mounted for rotation in bearings in spaced brackets 37 (Figs. 6 and 9) secured to the frame 10. The armature shaft of a motor 42 is provided with a pulley 44 which is connected by a belt 45 with a pulley 46 mounted for rotation upon the countershaft 41. The pulley 46 is adapted to be brought into and out of driving relation with the shaft 41 by a clutch mechanism C (Figs. 2, 7 and 9) which is actuated by a foot treadle 43.

The front end of a lever 52 (Figs. 1, 2 and 4) is rotatably mounted on a rod 53 extending between and secured to the spaced supports 35. The lever 52 is formed with spaced parallel arms 54 extending adjacent opposite faces of a disc 50 fixed upon the shaft 38. Each of the arms 54 carries a roll 55 engaging a cam groove 51 in the disc 50. A block 56 is pivotally connected to the other end of the lever 52. One end of a rod 57 (Figs. 1 and 4) is secured to the block 56 and its other end is secured to a block 58. The block 58 is bifurcated to provide spaced vertically extending walls 59 (Fig. 2) which are connected at their upper ends by spaced walls 60 (Figs. 1, 3 and 4). A shaft 61 extends through aligned bearings in the spaced walls 59 and is secured at its ends to the arms 25. A worm wheel 63 is positioned between the spaced walls 59 and is formed integral with a hub 62 which is rotatably mounted in the aligned bearings in the spaced walls 59. The hub 62 is keyed upon an eccentric 471 rotat-

ably mounted upon the shaft 61. The worm wheel 63 is adapted to be engaged by a worm 64 upon a shaft 65 which is mounted for rotation in bearings in the spaced walls 60. The shaft 65 is provided with a handle 66 by which it may be turned manually and thereby shorten or lengthen the connection between the arms 25 and the lever 52.

The buck 15 comprises a U-shaped body 70 (Figs. 1, 2, 4 and 5), the top of which is closed by a pervious pressing surface comprising a wire mesh screen 71, the edges of which are turned down over the side walls of the body 70 and secured thereto by a clamping band 72. A pervious pad 73 is positioned upon the screen 71 and is covered by a cloth 74, the edges of which are folded over the side walls of the body of the buck and secured by a tie string 75. The construction of the head 14 is similar to that of the buck and comprises an inverted U-shaped body 76 covered by a screen 77 and a cloth 78 between which is interposed a pervious pad 79. The top wall 70 of the head is provided with a plurality of uniformly distributed perforations 80.

Steam heating coils 76 and 77 (Figs. 1, 2, 4 and 5) are positioned inside the chambers formed within the hollow buck and head between the pervious pressing faces and the bottom and top walls thereof, respectively, said heating coils serving to supply heat to the chambers and to the work being pressed between said pressing faces. A steam inlet pipe 81 is connected to the inlet of the coil 76 and a steam exhaust pipe 80 is connected to the outlet of the coil 76. The steam inlet pipe 81 and exhaust pipe 80 are connected with the inlet and outlet for the coil 77 by flexible conduits 82 and 83, respectively. The steam pipe 81 is provided with a branch pipe 86 which is connected to a spray nozzle 87 fitted in an opening in the bottom wall 70 of the buck 15. A valve 88 is interposed in the branch pipe 86 for controlling the supply of steam to the spray nozzle 87. The valve stem 101 of the valve 88 projects through the casing of the latter. The valve 88 normally is maintained closed by a spring 108 surrounding the valve stem 101 and interposed between the casing of the valve 88 and a collar 109 fixed upon the valve stem.

A conduit 89 is secured at one end to the bottom wall 70 of the buck in communication with an opening 90 (Figs. 1, 2, 4 and 5) therein. The wall of the opening 90 is formed with a valve seat to receive a valve 91 for opening and closing the opening 90. The conduit 89 is connected through a T-fitting 92 to a conduit 93 which is connected to the inlet of a suction fan 94 (Figs. 2, 3 and 6). The valve 91 is provided with a valve stem 95 which projects through and is slidably mounted in a bushing 96 secured in the T-fitting 92. The valve 91 normally is held in its closed position by a spring 97 surrounding the valve stem 95 and interposed between the bushing 96 and a collar 98 fixed upon the valve stem. The outlet of the suction fan 94 is connected by a conduit 120 with the inlet of a dehydrating device 121 having an outlet communicating with the atmosphere. The suction fan 94 is driven by a motor 122 supported upon a bracket 123 secured to and projecting from one side of the wall of the frame 10.

A lever 99 (Figs. 1, 2 and 4) is pivotally secured at one end to the frame 10 and its other end projects into an opening 100 in a block 101 secured to the lower end of the valve stem 95.

One end of a rod 102 is pivotally connected to the lever 99 intermediate its ends. The other end of the rod 102 is pivotally connected to one end of a foot lever 103 which is pivotally mounted intermediate its ends upon a rod 104 extending between the side walls of the frame 10. A roller 105 carried by the lever 99 intermediate its ends is adapted to engage the surface of a cam 106 (Figs. 1, 2 and 6) fixed upon the main drive shaft 38.

One end of an arm 110 (Figs. 1 and 4) is pivotally mounted upon a projection formed on the casing of the valve 88 so as to project under the end of the valve stem 107. The other end of the arm 110 is forked and embraces a rod 111 and normally rests upon a collar 112 fixed to the rod. The lower end of the rod 111 is pivotally connected to one end of a foot treadle 113 mounted upon the rod 104. A lever 114 is pivotally mounted at one end to the frame 10 and its other end projects through an opening 115 in a block 116 integral with the rod 111. A cam follower 117 carried by the lever 114 is adapted to engage the surface of a cam 118 (Figs. 2, 4 and 6) fixed upon the drive shaft 38.

The cam grooves 51 in the disc 50 include portions 26 and 27 concentric with the axis of the shaft 38 which receive the rolls 55 when the head 14 is in its extreme lower and upper positions respectively. When the rolls 55 engage the concentric portions 27, the head is held stationary in its upper position, and when they engage the portions 28, it is held pressed against the buck to exert upon work disposed upon the latter a constant pressure which is the maximum pressure for which the machine is adjusted by the eccentric 411. The cam groove portions 26 and 27 (Figs. 1 and 4) are connected by cam groove portions 28 and 29 which cause movement of the head 14 from its extreme upper to its extreme lower positions and vice versa respectively. As the head is moved from its extreme upper position, the roll 30 successively engages the portions 33 and 34 of the groove 31 to cause the head to swing to a position parallel to and spaced from the buck and then move into engagement with the buck. The cams 118 and 106 are provided with raised portions 47 and 48 (Fig. 1) respectively, which are arranged to engage the cam follower 117 and the roll 105 successively to open the steam valve 88 to spray steam momentarily through the nozzle 87 and then, at termination of spray, open the suction valve 91. The valves 88 and 91 are maintained closed when the cam follower 118 and roll 105 engage the remaining portions of their respective cams. The cam disc 50 and cam 106 are arranged upon the drive shaft 38 so that the valve 91 is opened only while the head engages the buck unless actuated by the foot treadles 103 and 113. In other words, the shapes and relative angular positions on the shaft 38 of the cams 50, 106 and 118, with respect to their several cam followers, are such as to cause the steam valve 88 to close and the suction valve 91 thereafter to open, both while the rolls 55 are in the concentric portions 26 of the grooves 51 and the work consequently held under constant maximum pressure between the press elements 14 and 15.

As will be obvious from Figs. 1, 2, 4 and 5, the chambers formed within the hollow head 14 and buck 15 are substantially coextensive in area with the previous work engaging pressing faces thereof, while the distribution of the perforations 69 (see also Fig. 3) over the top wall 70' of the head is

such as to render said wall foraminous over an area likewise substantially coextensive with said faces. Consequently, when suction is applied to the hollow buck, a flow of atmospheric air is induced through the head and work, said air being evenly distributed over the work, being caused to pass completely and directly through the latter at right angles, and being preheated by the steam coils 71 during its passage through the hollow head, whereby the work is quickly and evenly dried.

The motor 42 is secured upon a platform 130 (Figs. 1, 2, 6 and 7) which is slidably mounted upon spaced rods 131 extending between the side walls of the frame 10. A rod 132 passing through an opening in one of the side walls of the frame 10 is secured at one end to the platform 130 and is secured at its other end to one end of a manually operable lever 133 which is pivotally mounted intermediate its ends upon a bracket 134 secured to the frame 10. The motor 42 normally is urged to the left as viewed in Fig. 6 by a pair of springs 135, each of which is secured at one end to the platform 130 and at its other end to the frame 10.

The pulley 44 is composed of two complementary parts 136 and 137 (Figs. 1 and 7) which cooperate to provide a V-shaped groove in which the belt 45 is received. The part 136 is fixed upon the armature shaft of the motor 42 while the part 137 is slidably keyed thereto. By adjusting the position of the pulley part 137 relative to the part 136, the effective size of the pulley 44 may be varied to control the speed of operation of the machine. The means for adjusting the position of the pulley part 137 comprises a lever 138 pivotally connected at one end to a bracket 139 secured to the platform 130. The other end of the lever 138 is pivotally secured to a block 140 carried by one end of an adjusting rod 141 extending forwardly through the front wall of the frame 10. The lever 138 is formed with a ring-like intermediate portion 129 surrounding the armature shaft of the motor 42 and provided with diametrically oppositely positioned projections 144 adapted to engage the movable pulley part 137. The rod 141 is provided with a threaded portion 142 engaging a nut 143 pivotally carried by a bracket secured to the motor 42. The pulley part 137 is held in engagement with the projections 144 by the tension of the belt 45.

One element of the clutch C comprises a drum 145 (Figs. 6, 7, 8 and 9) surrounding the counter shaft 41 and formed integral with the pulley 46. The other element of the clutch C comprises a pair of internally expanding brake or clamp shoes 127 (Fig. 8) which are expanded by cams 128 fixed upon each of the spaced shafts 146 which are mounted for rotation in a disc 147 keyed upon the countershaft 41. A drum 200 is formed integral with the disc 147 and is arranged to be engaged by a brake 164 when the clutch is disengaged. An operating arm 148 is fixed upon each of the shafts 146 and each carries a cam follower 149 which is urged toward the counter-shaft 41 by a spring 150. A collar 151 is rotatably and slidably mounted upon the shaft 41 and is provided with a groove 152 adapted to be engaged by rolls 153 carried by the free ends of a yoked arm 154 forming one of the arms of a bell crank lever 155 which is pivotally mounted upon the frame 10. An annular cam 166 surrounds the countershaft 41 and projects rearwardly from the collar 151 so as to engage the cam followers 149 and control movement of the arms 148 to engage or disengage the clutch C. Another arm 156 of

the bell crank lever is pivotally connected to one end of a link 151, the other end of which is pivotally connected to an ear 158 projecting from the hub 159 of the foot treadle 43 which is secured upon the shaft 104 rotatably mounted in the frame 10. The foot treadle 43 is provided with a portion 43' extending rearwardly from its hub 159. A counterweight 161 is secured upon a sleeve 162 (Fig. 2) which is fixed upon the shaft 104. The counterweight serves to hold the treadle 43 in either its operative or inoperative positions. A third arm 163 of the bell crank 155 carries the brake shoe 164 adapted to engage the drum 200 of the clutch C when the clutch is disconnected.

Mechanism is provided for disengaging the clutch C automatically to stop rotation of the drive shaft 38 when the head engages the buck and when the head is in its uppermost position. This mechanism comprises a cam 170 (Figs. 2, 6, 7 and 9) fixed upon the shaft 38 and provided with raised portions 171 at diametrically opposite points on its periphery. A lever 172 is pivotally mounted intermediate its ends upon the frame 10. One end of the lever 172 carries a roll 173 adapted to engage the cam 170. The other arm 174 of the lever 172 projects downwardly adjacent a bar 175 and carries a roll 176 (Fig. 10) which projects into a slot 177 in the rod 175. A rod 178 is provided with a threaded portion 179 engaging a threaded opening in the bar 175 and is adapted to be adjusted into or out of engagement with the lever arm 174. The other end of the rod 178 extends through the front wall of the frame 10 and is provided with an operating knob 180. The bar 175 is provided with a forked rear end 181 embracing a pin 182 carried by a lever 183 near one end thereof. The other end of the lever 183 is pivotally mounted upon an arm 184 projecting upwardly from and formed integral with the bar 175. A spring 185 is secured at one end to the bar 175 and at its other end to the pin 182. The lever 183 is provided with a slot 186 engaged by a pin 187 projecting from the yoked arm 154. The arm 184 is provided with a rearwardly extending tongue 188 adapted to be engaged by the forward edge of the lever 183.

Steam is supplied continuously to the coils 76 and 77 to heat the head and buck. To start the machine in operation, the foot treadle 43 is depressed to slide the cam 166 to the right as viewed in Figs. 7 and 9, and thus turn the arms 148 to expand the brake shoes 127 and engage the clutch C. In this way, power is supplied to rotate the shaft 38. The cams 50, 106, 118 and 170 are so arranged upon the shaft 38 as to actuate the instrumentalities associated therewith in desired timed relation. As the shaft 38 is rotated through one complete revolution, the cam grooves 51 in the disc 50 cause the head 14 to move from its uppermost position toward the buck 15 to engage the latter under pressure and then return to its uppermost position. The cam grooves 51 in the disc 50 are so formed that the head 14 is held in its uppermost position and in engagement with the buck for predetermined lengths of time. When the head is in its uppermost position a garment may be spread upon the surface of the buck. As the head is approaching the buck and is within a predetermined distance therefrom, the cam 118 causes the steam valve 88 to open to spray steam through the nozzle 87 to moisten the garment on the buck. The steam valve 88 remains open until the head has been in engagement with the buck for a short interval of time and is then

caused to close by operation of the cam 118. A short interval of time thereafter, while the head still is in engagement with the buck, the cam 106 causes the suction valve 91 to open. When this valve is opened, air is drawn by the suction fan 94 through the perforations 69, as illustrated in Fig. 4, into the head 14 and through the garment. This air is heated as it passes through the head and facilitates removal of moisture from the garment. Just before the head starts to move out of engagement with the buck, the operation of the cam 106 causes the suction valve 91 to close and the head then returns to its uppermost position and the pressed garment is removed from the buck and another garment spread thereupon. The clutch C may be disengaged to stop operation of the machine by depressing the portion 43' of the foot treadle 43. Disengagement of the clutch C moves the bell crank 155 together with the arm 163 to bring the brake shoe 164 in engagement with the drum 200 to stop rotation of shaft 41.

The pressure exerted by the head upon the garment and buck may be adjusted by turning the shaft 65 to change the length of the connection between the arms 25 and the lever 52. The speed of rotation of the shaft 38 may be varied from between about 8 to 15 revolutions per minute by rotating the rod 141 to swing the lever 138 either clockwise or counterclockwise as viewed in Fig. 7, and thus control the distance between the pulley parts 136 and 137 to change the effective size of the pulley 44. In order to facilitate making this adjustment, the tension of the belt 45 is relieved by turning the lever 133 to move the assembly for the motor 42 to the right as viewed in Fig. 6. After the adjustment has been made, the lever 133 is released and the springs 135 move the motor assembly to the left, as viewed in Fig. 6, to hold the belt 45 under desired tension.

When the rod 178 is adjusted to the full line position shown in Fig. 10, the machine may operate continuously through successive or recurrent cycles. In such case, the enlargements 171 upon the cam 170 cause the lever 172 to swing upon its pivot but because of the position of the rod 178, the arm 174 of the lever 172 merely moves back and forth in the slot 177 in the bar 175 without performing any operative function. However, when the rod 178 is adjusted to the dotted line position shown in Fig. 10, the lever 172 becomes locked to the bar 175. Consequently, when one of the enlargements 171 upon the cam 170 engages the roll 173, the lever 172 is caused to swing in a clockwise direction as viewed in Fig. 9 to move the bar 175 to the left. Since the spring 185 connects the bar 175 with the pin 182 carried by the lever 183, a resilient connection is thereby provided between the bar 175 and the lever 183 which causes the lever 183 to be moved to the left as viewed in Fig. 9 when the bar 175 is moved to the left. At the same time, the cam 166 is moved to the left to disengage the clutch C inasmuch as the pin 187 engages the slot 186 in the lever 183. The raised portions 171 are so positioned upon the cam 170 that the clutch is disengaged to stop operation of the chain of operations when the head 14 is in its uppermost position and again when the head is in engagement with the buck. It will be understood that when the operation of the machine is thus stopped it may be again started by depressing the foot treadle 43.

The operation of the essential instrumental-

ties of the machine in the preferred timed relation is illustrated diagrammatically in Fig. 11. In Fig. 11, the concentric circles H, T, V and S represent the action during one complete simultaneous revolution of the cams 50, 170, 106 and 118, respectively, which control the movement of the head, the automatic disengagement of the clutch, the operation of the vacuum valve, and the operation of the steam spray valve, respectively. The circles are divided by radial lines 15° apart. The full line portions *a* and *b* of the circle H represent the periods in which the portions 27 and 26 of the cam grooves 51 are operative, namely, the periods in which the head remains in its uppermost position and in its lowermost position, respectively. Thus, when the cam disc 50 has rotated 150° the head engages the buck and remains in engagement with the buck until the cam has rotated 210°. The head is in its uppermost position during the first and last 15° of rotation of the cam disc 50.

If the rod 178 is adjusted to its dotted line position shown in Fig. 10, the machine will stop in the middle of the periods in which the head is held in its uppermost and lowermost positions as indicated by the full line portions *c* and *d* of the circle T which represent the periods in the rotation of the cam 170 when the enlargements 171 thereon are operative to disengage the clutch C.

The full line portion *e* of the circle S represents the period during rotation of the cam 118 when the steam spray valve 88 is open. Thus, this valve is opened when the cam 118 has rotated approximately 127½° of its cycle of movement and remains open until the cam 118 has completed substantially 157½° of one revolution whereupon the valve 88 is closed and remains closed while the cam 118 completes one revolution. Thus, it will be noted that the steam spray valve is opened just before the head reaches its lowest position and remains open for a short period of time while the head is held in a position to exert its full or maximum pressure upon work interposed between it and the buck. Shortly after the steam valve 88 has closed and when the cam 106, represented by the circle V in Fig. 11, has completed about 165° of one revolution and the work is still held under pressure, the cam 106 causes the suction valve 91 to open and this valve remains open until the cam 106 has completed about 115° of one revolution or until just before the head starts to rise and thereby releases the pressure on the work.

We claim:

1. In a pressing machine, in combination, cooperating press elements, a shaft, means including a cam on said shaft for closing said press elements upon the work to exert and maintain a substantially constant pressure thereon and for thereafter opening said elements to release said pressure, means for supplying steam to the work, a valve for controlling the steam supply, and means including a cam on said shaft for operating said valve, said last named cam being so shaped and positioned on said shaft with respect to said first named cam as to cause said valve to open when said elements are closed upon the work and to close while said first named cam holds said press elements in position to exert substantially constant pressure on the work.

2. In a pressing machine, cooperating press elements having previous work-engaging pressing faces, means for closing said elements upon the work to exert and maintain pressure thereon and for thereafter opening said elements to release said pressure, one of said elements having a chamber communicating with the pressing face thereof, means for supplying steam to said chamber to moisten the work and for discontinuing the same, and means for applying suction to said chamber while the work is under pressure and thereby inducing a flow of air through the other of said elements and through both pressing faces and work, said other element being hollow and having a wall, opposed to the pressing face thereof, which is foraminous throughout an area at least substantially coextensive with the work-engaging areas of said pressing faces, whereby the air passing through the work is substantially evenly distributed thereover.
3. In a pressing machine, a work supporting buck, a pressing head, said buck and head having previous work-engaging pressing faces, means for moving said head toward said buck to exert and maintain pressure on work supported by said buck and for thereafter moving said head away from said buck to release said pressure, said buck having a chamber communicating with the pressing face thereof and substantially coextensive in area with the work engaging area of said pressing face, means for supplying steam to said chamber to moisten the work and for discontinuing the same, and means for applying suction to said chamber while the work is under pressure and thereby inducing a flow of air through said head and through both pressing faces and work, said head being hollow and having a wall, opposed to the pressing face thereof, which is foraminous throughout an area at least substantially coextensive with the work-engaging areas of said pressing faces, whereby the air passing through the work is substantially evenly distributed thereover.
